(57) **CLAIM**

The ornamental design for an absorbent article package, as
shown and described.

DESCRIPTION

FIG. 1 is a perspective front view of an absorbent article
package embodying the new design;

FIG. 2 is a front view of the design shown in FIG. 1;

FIG. 3 is a right side view of the design shown in FIG. 1;

FIG. 4 is a back view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

In the figures described above, the broken lines depict
environmental subject matter only and form no part of the
claimed design. Solid lines form the claimed design. The
shaded surfaces represent a contrast in appearance.

1 Claim, 6 Drawing Sheets
